UNITED STATES PATENT OFFICE.

MARTIN NYSTROM, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

COMBINED PHONOGRAPH AND RADIO RECEIVING APPARATUS.

Application filed June 23, 1924. Serial No. 721,709.

This invention relates to a combination phonograph and radio receiving apparatus and it is the object of my invention to provide such an apparatus which may employ a single amplifying horn, which horn may be connected to either the phonograph or the radio apparatus, at will.

More specifically the object of my invention is to provide a combined phonograph and radio receiving apparatus having a common amplifying horn and having a pivoted neck for the horn which may be adjusted so as to register with the tone-arm of the phonograph, or with the arm leading to the radio loud speaker.

Other objects will be in part apparent and in part pointed out during the progress of the description.

In the drawings in which I have illustrated a preferred embodiment of my invention,

Fig. 1 is a front elevation of a portion of a cabinet containing my apparatus.

Fig. 2 is a vertical section through a portion of the cabinet.

Fig. 3 is a section on the line 3—3 of Fig. 2, and Fig. 4 is a section on the line 4—4 of Fig. 2.

Referring now to the drawings, 1 designates a cabinet of any suitable form containing a phonograph and a radio receiving set. This cabinet may take the form shown in my copending application, Serial No. 713,128, filed May 14, 1924, or it may be of any other form desired. The phonograph comprises the usual turn-table 2, reproducer 3 and tone-arm 4 mounted on a motor-board 5. The radio-receiving set is indicated generally at 6 and may be of any type desired. The loud speaker for the set is indicated at 7 and, of course, is connected to the set 6 by a suitable conductor 8. Extending towards the front of the cabinet is an amplifying horn 9, the bell mouth of which is received in a block 10, which forms in effect a portion of the horn.

In the normal operation of a phonograph sounds are transmitted through the tone-arm and through a suitable neck connecting the tone-arm to the block 10, and thence through the block 10 to the horn 9, as is well known in the art.

On the under side of the motor-board 5 I provide an element 11 having hollow arms

12 and 13. The arm 12 is fastened to the motor-board in such a position that the opening therein will register with the opening through the tone-arm so the sounds from the tone-arm may pass therethrough. The arm 13 is preferably made integral with the arm 12 and the element 11 may be further supported on the bottom of the motor-board by any suitable means 14. The arm 13 extends to the radio loud speaker 7 whereby sounds may be transmitted from the receiver through said arm 13. The under side of the element 11 is preferably made with an arcuate surface 15, the center of which is at the center of the pins 16. The element 11 is rigidly secured to the block 10 by means of a framework 17 fastened to the block 10, as by screws 18, and to the element 11 as by bolts 19.

The framework 17 is provided with a collar 20 in which is received the enlarged end 21 of a hollow neck 22. The neck 22 is pivoted on the pins 16, as will be evident from an inspection of Figs. 2 and 4. The pins 16 are set in lugs 16' on the framework 17. The end 21 of the neck 22 is cut on a bias both ways from the center, as shown in Fig. 2, whereby rotation about the pins 16 is permitted.

The upper end of the neck 22 is provided with an arcuate extension 23 adapted to contact with the surface 15, and the wall of the neck 22 is flanged, as at 24, to provide a bearing against said surface 15. At a point on the neck 22 adjacent to the upper end thereof is provided a lug 24' in which slides a pin 25 carrying a brake 26, also of arcuate surface, to contact with the surface 15. The brake 26 is held in yielding engagement with the surface 15 by means of the spring 27. Movement of the neck 22 about the pins 16 is caused by movement of the rod 28 passing through the wall 29 of the cabinet and provided on its outer end with a suitable handle 30. At its inner end it is pivotally mounted at 31 to an integral arm 32 on the neck 22.

In operation, and assuming that the phonograph is to be used, the rod 28 is actuated to bring the neck 22 into the position shown in Fig. 2, and it is evident that the neck will be yieldingly held in this position by the brake 26 and that the sounds from the phonograph will be transmitted through the tone-arm 4, arm 12, neck 22 and block

10 to the horn 9. If the radio set is to be used the rod 28 is pulled to the right, in Fig. 2, until the neck 22 comes in registry with the arm 13. It will be understood, of course, that the movement of the neck 22 is limited positively by the engagement of the biased portions on the bottom thereof with the portion of the framework fastened to the block 10. If it is desired to modify the volume of sound coming from either the phonograph or the radio, it is possible to do so by a movement of the rod 28 to cause a partial movement of the neck 22 and to cut off a portion of the sound transmitted thereto.

From the above it will be seen that I have provided a combined phonograph and radio receiving apparatus employing a common horn and also having a common neck for the horn, which is adjustable to either of two positions to serve in effect as a switch from the phonograph to the radio loud speaker, or vice versa.

I am aware that changes in the form, construction and arrangement of parts may be made without departing from the spirit and without sacrificing the advantages of the invention and I reserve the right to make all such changes as fairly fall within the scope of the following claims.

I claim:

1. In a device of the character described, a phonograph, a radio loud speaker, a fixed amplifying horn, and a pivoted neck adapted to connect said amplifying horn to either said phonograph or said loud speaker.

2. In a device of the character described, a phonograph, a radio loud speaker, a fixed amplifying horn, a pivotally movable neck adapted to connect said amplifying horn to either said phonograph or said loud speaker, and means for limiting the movement of said neck.

3. In a device of the character described, a phonograph, a radio loud speaker, an amplifying horn, a pivoted neck adapted to connect said amplifying horn to either said phonograph or said loud speaker, and a brake associated with said neck to yieldingly hold it in its adjusted position.

4. In a device of the character described, a phonograph, a radio loud speaker, a fixed amplifying horn, a pivoted neck adapted to connect said amplifying horn to either said phonograph or said loud speaker, a cabinet containing said elements, and means operable from the outside of said cabinet to operate said neck.

5. In a device of the character described, a fixed amplifying horn, a phonograph, a radio loud speaker, and a neck pivoted to said horn and adapted to be brought into

operative relationship with either said phonograph or said loud speaker.

6. In a device of the character described, a cabinet having a motor-board, a tone-arm mounted thereon, an element mounted beneath said motor-board and comprising two arms, one registering with said tone-arm and the other adapted to be connected to a radio loud speaker, a fixed amplifying horn, and a neck pivoted to said horn and adapted to register with either of the arms of said element.

7. In a device of the character described, a cabinet having a motor-board, a tone-arm mounted thereon, an element mounted beneath said motor-board and comprising two arms, one registering with said tone-arm and the other adapted to be connected to a radio loud speaker, an amplifying horn, a neck pivoted to said horn and adapted to register with either of the arms of said element, and a yieldable brake to hold said neck in adjusted position.

8. In a device of the character described, a motor-board, a tone-arm mounted thereon, an element supported beneath said motor-board and having two arms, one registering with said tone-arm and the other adapted to be connected to a radio loud speaker, a fixed amplifying horn, a framework connecting said horn and said element, and a neck pivoted in said framework and adapted to register with either of the arms of said element whereby sounds may be transmitted to said horn from either said tone-arm or said loud speaker.

9. In a device of the character described, a motor-board, an element supported beneath said motor-board and having two arms, one adapted for connection with a phonograph, and the other for connection with a radio loud speaker, said element having an arcuate under surface, a fixed amplifying horn, and a neck pivotally mounted on said horn and having an arcuate portion contacting with the arcuate surface of said element, for the purpose set forth.

10. In a device of the character described, a motor-board, an element supported beneath said motor-board and having two arms, one adapted for connection with a phonograph, and the other for connection with a radio loud speaker, said element having an arcuate under surface, a fixed amplifying horn, a neck pivotally mounted on said horn and having an arcuate portion contacting with the arcuate surface of said element, an arm on said neck, and an operating rod pivotally connected to said arm, for the purpose set forth.

MARTIN NYSTROM.
